Primary Examiner—Freda Nunn
Attorney, Agent, or Firm—Janis Biksa; Peters, Verny, Jones & Biksa[57] **CLAIM**

The ornamental design for a tripod lamp, as shown and described.

DESCRIPTION

FIG. 1 is a perspective view of a tripod lamp showing my new design;

FIG. 2 is a front view of the design of FIG. 1;

FIG. 3 is a left side view of the design of FIG. 1, the right side being a mirror image thereof;

FIG. 4 is a back view of the design of FIG. 1;

FIG. 5 is a top view of the design of FIG. 1; and,

FIG. 6 is a bottom view of the design of FIG. 1.

The broken lines are shown in the views for illustrative purposes only and form no part of the claimed design.
